JAMES LEAK, OF GEDDES, NEW YORK, ASSIGNOR TO HIMSELF, THOMAS G. WHITE, AND WILLIAM HOLMES.

Design No. 4,273, dated August 2, 1870.

DESIGN FOR A FLOWER-POT.

The Schedule referred to in these Letters Patent and making part of the same.

To all whom it may concern:

Be it known that I, JAMES LEAK, of Geddes, Onondaga county, assignor to myself and THOMAS G. WHITE, of Geddes, aforesaid, and WILLIAM HOLMES, of Syracuse, New York, have invented and produced a new and original Design for a Flower-Pot, in imitation of a section of the trunk of a tree, with the bark and knots as naturally seen, in the general manner shown, of which the following is a specification.

The nature of my design is fully represented in the

accompanying photographic illustration, to which reference is made.

I claim as my invention—

The design for a flower-pot in imitation of a section of the trunk of a tree, with the bark and knots as naturally seen, substantially as shown.

JAMES LEAK.
